UNITED STATES PATENT OFFICE.

AARON MARCELLUS, OF BALLSTON LAKE, NEW YORK.

SIGNALING ATTACHMENT FOR TYPEWRITERS.

Application filed February 1, 1927. Serial No. 165,203.

The present invention is directed to improvements in typewriters, and more particularly to a signaling attachment therefor.

The primary object of the invention is to provide a device of this character so constructed that it can be applied to a standard typewriter and when in place thereon is operable to indicate to the operator that the lower edge of the letter sheet has reached the predetermined point, thus enabling the operator to type letters having their lower, or last typed line uniform.

Another object of the invention is to provide a device of this character wherein the signaling device may be adjusted in order that the position of the last line of typing may be regulated; and further to provide means whereby the device can be attached to typewriter carriages of various sizes.

20 In the accompanying drawings:

Figure 1 is a fragmentary front view of a typewriter showing the device in place thereon.

Figure 2 is a transverse sectional view 25 through the device.

Figure 3 is a transverse sectional view, showing the signaling device after being released.

Figure 4 is a rear view of the device.

30 Figure 5 is a sectional view on line 5—5 of Figure 3.

Figure 6 is a fragmentary top plan view of the guide and associated strip.

Referring to the drawings, 1 designates 35 the paper rest, 2 the bead thereof, and 3 the platen, all of which are of conventional form.

The attachment comprises a resilient clamping sleeve 4 which has associated therewith a jaw plate 5 and a relatively long jaw plate 6 provided, respectively, with actuating handles 7 and 8, the former having a slot 9 therein, the purpose of which will be later explained. As clearly shown in Figures 2 and 3 the sleeve 4 of the clamp engages the bead 2 and at which time the jaw 5 engages the front face of the rest 1 while the jaw 6 extends longitudinally of the rear face thereof.

40 As shown in Figure 1 of the drawings, a pair of letter sheet engaging clamps 10 are employed and in order to support these clamps a tube 11 is provided and secured in one end thereof is a rod 12 having an

angular extension 13, and telescopically engaged in said tube is a rod 14 which is also provided with an angular extension 15, the respective extensions being fitted in the terminal coils 16 formed upon the outer ends of the rod 17, the inner ends of said rod being provided with hooks 18 designed to slidably engage the jaw plate 6, thus sustaining the associated parts in proper relation with respect to the paper rest. 55

The clamps 10 comprise inner and outer resiliently connected arms 19 and 20, respectively, the latter having resilient ears 21 for slidably engaging the tube 11, said tube being formed with recesses 22 for engagement with said ears to hold the clamps 10 in adjusted 60 positions upon the tube in order that the clamps will be properly positioned with respect to the signaling device. This signaling device comprises the sheet metal guide 23 having inturned flanges 24, said flanges having their inner edges spaced and provided with diametrically opposed pointers 25, the purpose of which will be later explained. The bottom of the guide 23 is provided with a tongue 25' adapted to pivotally engage the 65 slot 9 of the handle 7 in order that the guide may rock.

70 Slidably retained in the guide 23 is a strip 26 formed from metal which is somewhat pliable and is bent into loop formation, as shown in Figures 2 and 3 of the drawings. The rear end of this strip is provided with spaced wings 27 and swingable between said wings is a bell 28, pivoted as at 29 to said strip. Fixed to the strip 26 between the 75 wings 27 is a piece of felt 30 and upon which the bell rests when the device is held by the letter sheet 31 so as to prevent sounding of the bell when the carriage is shifted, or subjected to other movement. 80

Upon reference to Figure 1 it will be observed that the letter sheet 31 is engaged upon the upper surface of the strip 26 and holds the same in a position to cause the bell 28 to rest upon the felt strip 30 and prevent 85 sounding thereof. The arms 19 of the clamps 10 will hold the letter sheet 31 taut, in order that it will not bulge or bend at its point of contact with said strip. As soon as the lower edge of the sheet 31 disengages 90 the adjacent end of the strip 26, said strip will rock to the position as shown in Figure 3, whereupon the rear end of said strip will 95

swing inwardly, thus permitting the bell to swing freely and sound an alarm to indicate that the sheet 31 has reached a predetermined point.

5 The strip 26 is provided with transverse ribs 32 which may be numbered and are capable of being selectively brought into registration with the pointers 25 to permit the operator to set the strip in the guide 23 at predetermined points in order that the distance of the last printed line upon the sheet 31 may be accurately determined.

It will be obvious that the arms 20 of the clamps have their lower ends resting upon 15 the platen 3 in such position that the paper sheet 31 will be deflected away from the strip 26 to prevent any possibility of the same contacting therewith.

Since the tube 11 telescopically engages the 20 rod 14, said rod and tube and the associated parts can be adjusted to fit paper rests of various sizes, which is readily accomplished due to the fact that the hooks 18 are 25 slideable upon the jaw plate 6. I have shown the attachment in use upon the paper rest of an Underwood typewriter, but it will be of course understood that by minor changes the attachment can be used in connection with other makes of typewriters. The jaw plate 6 30 may be provided with a series of notches 32

for engagement with the hooks 18 in order to maintain the same in adjusted positions.

Having thus described the invention, I claim:

1. The combination with the paper rest 35 and platen of a typewriter, of a clamp removably engaged with the paper rest, a guide pivotally connected with the clamp, a strip adjustably mounted in the guide and having a bell pivotally connected to its rear end, 40 said strip being held against pivotal movement when a letter sheet engaged with the platen engages the forward end thereof, said strip being releasable for pivotal movement to sound the bell when the said sheet disengages the forward end of said strip. 45

2. The combination with the paper rest and platen of a typewriter, of a clamp detachably engaged with the paper rest, a strip 50 adjustably associated with the clamp and having a signaling device upon its rear end, clamps adjustably associated with the paper rest for holding a letter sheet positively engaged with the forward end of the strip, said strip being permitted to rock when the letter sheet disengages the forward end of the 55 same to permit sounding of the signaling device.

In testimony whereof I affix my signature.
AARON MARCELLUS. [L. s.]
